US00D445090S

(12) **United States Design Patent** (10) Patent No.: **US D445,090 S**
Payne et al. (45) Date of Patent: ** Jul. 17, 2001

(54) **SCANNER/PRINTER POWER CORD
TETHER**

Primary Examiner—Susan J. Lucas
Assistant Examiner—Jennifer Rivard

(75) Inventors: **David M. Payne**, Meridian; **Joseph M. Wax**, Boise, both of ID (US)

(57) **CLAIM**

The ornamental design for a scanner/printer power cord tether, as shown and described.

(73) Assignee: **Hewlett-Packard Company**, Palo Alto, CA (US)

DESCRIPTION

(**) Term: **14 Years**

(21) Appl. No.: **29/132,490**

(22) Filed: **Nov. 8, 2000**

(51) LOC (7) Cl. **13-03**

FIG. 1 is a perspective view of the scanner/printer power cord tether showing our new ornamental design.

(52) U.S. Cl. **D13/139.7**

FIG. 2 is a rear elevational view thereof.

(58) Field of Search **D13/137.4, 139.7;
439/502, 650, 654, 638, 698**

FIG. 3 is a front elevational view thereof.

(56) **References Cited**

FIG. 4 is a left elevational view thereof.

U.S. PATENT DOCUMENTS

FIG. 5 is right elevational view thereof.

5,466,172 * 11/1995 Carstens et al. .... 439/502 X
5,855,494 * 1/1999 Blaszczyk et al. 439/502
6,190,199 * 2/2001 Bump et al. .... 439/502 X

FIG. 6 is a top plan view thereof.

* cited by examiner

FIG. 7 is a bottom plan view thereof; and,

FIG. 8 is a perspective view of another embodiment of a scanner/printer power cord tether.

The claimed design is shown broken away to indicate indeterminate length.
